F. J. VIERLING

PENCIL

Filed Aug. 6, 1927

UNITED STATES PATENT OFFICE.

FRANK J. VIERLING, OF MINNEAPOLIS, MINNESOTA, ASSIGNOR, BY DIRECT AND MESNE ASSIGNMENTS, TO SNAP-POINT PENCIL, INC., OF MINNEAPOLIS, MINNESOTA, A CORPORATION OF MINNESOTA.

PENCIL.

Application filed August 6, 1927. Serial No. 211,235.

My present invention has for its object to provide an extremely simple and highly efficient pencil, and to this end it consists of the novel devices and combinations of devices 5 hereinafter described and defined in the claims.

In the accompanying drawings, which illustrate the invention, like characters indicate like parts throughout the several views.

10 Referring to the drawings:

Fig. 1 is a view of the improved pencil principally in longitudinal central section;

Fig. 2 is a view of the pencil in elevation with the outer casing member removed;

15 Fig. 3 is a detail view with some parts sectioned on the line 3—3 of Fig. 1, on an enlarged scale;

Fig. 4 is a fragmentary detail view in longitudinal central section taken through 20 the telescoped portions of the casing members; and

Fig. 5 is a view corresponding to Fig. 1, but showing a slight modification.

The pencil includes a casing comprising 25 inner and outer tubular members 6 and 7 telescopically connected for relative longitudinal adjustment. Said inner casing member 6 has a long external screw thread 8 pressed in the body thereof, and said outer casing member 7 has a short internal screw thread 9 pressed in the body thereof and within which the thread 8 is seated. The outer or upper end portion of the inner casing member 6 is circumferentially expanded 30 at 10 to receive and removably hold an eraser 11. This expanding of the inner casing member 6 forms therein an internal annular shoulder 12, for a purpose that will presently appear. The lower or outer end 35 portion of the outer casing member 7 is drawn to a long tapered point 13 having a lead passage 14 at its contracted end and through which a lead may be endwise fed and held against lateral movement.

40 Extending longitudinally within the casing 6—7, at the axis thereof, is a long lead-feeding stem 15 having on its upper end a washer-like spring plate 16, which loosely rests on the shoulder 12. Said stem 15 extends loosely through a hole in the plate 16 at the center thereof and is bent laterally to 45 form a head 17 which bears on the upper surface of said plate and holds the lead-feeding stem 15 suspended therefrom.

A combined lead-holder and ejector 18 is 55 applied to the lower end portion of the lead-feeding stem 15 for holding a lead α , the upper end of which engages the lower end of said stem as a base of resistance. This lead-holder and ejector 18 is in the form of a 60 sleeve telescoped onto the lead-feeding stem 15 and has in its lower end portion a longitudinally extended slot 19 through which projects a stop lug 20 on said stem. This slot 19 performs another important function 65 in that it permits the respective portion of the lead-holder and ejector 18 to be slightly expanded by the insertion of the lead α therein to frictionally hold said lead suspended from the lead-feeding stem 15 in 70 axial alignment therewith. The slot 19 and stop lug 20 limit the projecting movement of the lead-holder and ejector 18 on the lead-feeding stem 15, and by an upward sliding movement of said holder and ejector on said 75 stem, the lead α may be ejected therefrom.

The inner casing member 6 is longitudinally slit at 21 transversely through the thread 8 and throughout the full length thereof to permit contracting and expanding 80 movements of the inner casing member 6 onto the outer casing member 7. The inner casing member 6 is further slit circumferentially thereof at the inner end of the slit 21 and extending in opposite directions 85 transversely thereof, as indicated at 22. The purpose of this slit 22 is to permit substantially the same circumferential contraction and expansion of the inner casing member 6 throughout the full length of the slit 21. 90

Obviously, by holding one of the casing members and rotating the other in respect thereto, the co-operating screw threads 8 and 9 will cause relative endwise adjustment to their casing members and thereby produce a 95 lead-feeding action either to project or retract the lead α in the lead passage 14. This relative adjustment of the casing members 6 and 7 causes a fine adjustment of the lead α . A coarse adjustment thereof may be had 100 to project the lead α by holding the casing member 7 in one hand with the thumb on the eraser 11 and applying pressure thereto to cause an endwise movement of the inner casing member 6 in the outer casing member 7, and at which time the screw thread 8 rides over the screw thread 9 with a ratchet-like 105 action causing contracting and expanding

movements of said inner casing member. A coarse adjustment of the lead α to retract the same may be had by drawing the two casing members 6 and 7 apart, and at which time the same ratchet-like action takes place between the threads 8 and 9.

Heretofore, pencils of this type have been found objectional due to the fact that the leads will be forced back into the pencil by endwise pressure applied to the outer projecting ends thereof such as writing. To overcome this objectionable feature, I provide automatic means, operated by pressure produced on a lead in a direction to force the same back into the pencil, to hold the casing members against a relative longitudinal adjustment tending to produce such movement. This automatic means, as shown, includes a truncated expanding member 23 having an axial hole through which the lead-feeding stem 15 loosely extends.

Below the expanding member 23 the lead-feeding stem 15 is upset to form a stop or abutment 24 on which said member rests. Said expanding member 23 extends into the lower end of the inner casing member 6 for expanding the same. Before the inner casing member 6 is telescoped into the outer casing member 7, the expanding member 23 is so held by the lead-feeding stem 15 from the plate 16 as to expand said inner casing, as shown in Fig. 2, and in which position the edges thereof at the slit 21 are in diverging relation. The expanding member 23 is self-centering in the inner casing member 6 and thereby holds the lead-feeding stem axially centered in the casing members 6 and 7.

To insert the inner casing member 6 telescopically into the outer casing 7, said inner casing member must be contracted thereby slightly forcing the expanding member 23 therefrom, and which action buckles the spring plate 26 and places the same under spring tension tending to draw the expanding member 23 into the inner casing member 6 and thereby expand the same into frictional contact with the outer casing member 7 with the threads 8 and 9 interlocked. With the expanding member 23 thus held, the casing members 6 and 7 may be relatively, longitudinally adjusted by a screw action produced by the interlocked threads 8 and 9.

The casing member 7 may be also relatively longitudinally adjusted to produce step by step lead-feeding action by straight end pressure applied to the casing member 6 to telescope the same into the casing member 7. Such pressure will cause the screw thread 8 to ride over the screw thread 9 with a ratchet-like action and such movement is permitted by the contracting movement of the inner casing member 6, due to the slits 21 and 22 therein.

During this contracting movement of the inner casing member 6, the expanding mem-

ber 23, due to the pressure applied thereto by said member, will be slightly forced out of the casing member 6 by further springing or buckling the plate 16. During the expanding movement of the inner casing member 6, the spring plate 16 will draw the expanding member 23 into the inner casing member 6. It will thus be seen that the casing members 6 and 7 may be readily adjusted by screw threads to produce a fine adjustment of the lead, or they may be adjusted to produce a step by step coarse adjustment thereof simply by straight-line telescopic movement of one of said members in respect to the other.

In case pressure is applied to the outer end of the lead α tending to force the same back into the pencil, said pressure will force the expanding member 23 into the casing member 6 and thereby further expand the same and prevent contracting movement of the inner casing member and hold the casing sections 6 and 7 together by frictional engagement and the interlocked screw threads 8 and 9.

A clip 24 is attached to the inner casing member 6 for holding the pencil in a pocket.

Referring now to the modification shown in Fig. 5, the structure and action of the pencil is the same as that just described, with the exception that a stiff washer or plate 25 is substituted for the spring plate 16, and the lead-feeding stem 26 is made of spring metal and bent laterally at 27 to form a spring section under strain to lift the expanding member 23 into the inner casing member 6 and expand the same.

The inner casing member 6 affords a chamber for spare leads and the expanding member 23 forms the bottom thereof. Spare leads may be inserted into this chamber or removed therefrom by removing the eraser 11 or through the slit 21. It will be noted that the spring plate 16 shown in Fig. 3 as well as the washer 25 are relatively narrow so as not to interfere with the insertion of the spare leads into the compartment provided therefore or the removal of the same therefrom.

What I claim is:

1. A pencil including a casing and a relatively longitudinally adjustable lead-feeding member, and means including a normally released device for locking the lead-feeding member to the casing, said device being arranged to be operated by a movement of the lead-feeding member produced by pressure on the lead in said member tending to force the same back into the pencil.

2. A pencil including a casing comprising a pair of relatively longitudinally adjustable members, a lead-feeding member arranged to partake of such adjustment with one of said members to produce either a lead-projecting or a lead-retracting movement,

- and means including a normally released device for locking the lead-feeding member to the casing and arranged to be operated by a movement of the lead-feeding device produced by pressure on the lead in said member tending to force the same back into the pencil.
3. A pencil including a casing comprising relatively longitudinally adjustable telescopically connected inner and outer casing members, said inner casing member being adapted to be expanded into contact with the outer casing member, a lead-feeding stem attached to the inner casing member for longitudinal adjustment therewith, and an expanding device on the lead-feeding stem arranged to be operated to expand the inner casing member into contact with the outer casing member, by a movement of the lead-feeding member produced by pressure on the lead in said member tending to force the same back into the pencil, to hold said members against relatively longitudinal adjustment.
- 10 4. A pencil including a casing comprising relatively longitudinally adjustable telescopically connected inner and outer members, a lead-feeding stem attached to the inner casing member for longitudinal adjustment therewith, said inner member being adapted to be expanded into contact with said outer member, and an expanding member on the lead-feeding stem arranged to be operated by a movement of the lead-feeding member produced by pressure on the lead in the lead-feeding stem tending to force the same back into the pencil, to expand said inner member into contact with said outer member and hold the casing members against relatively longitudinal adjustment.
- 15 5. The structure defined in claim 4 in which the expanding member is mounted in the inner end of the inner casing member for self-centering action in respect to the inner casing member and holds the lead-feeding stem centered in the casing.
- 20 6. The structure defined in claim 4 in which the expanding member is yieldingly held to permit contracting movement of the inner casing member during either lead-projecting or lead-retracting movements of the casing members.
- 25 7. The structure defined in claim 4 in which said lead-feeding stem is adapted to yield to permit the expanding member to move under the contracting action of the inner casing member.
- 30 8. A pencil including a casing comprising relatively longitudinally adjustable telescopically connected inner and outer mem-
- bers, a lead-feeding stem attached to said inner member for longitudinal adjustment therewith, said inner member being adapted to be expanded into contact with said outer members, an expanding member seated in said inner member and arranged to expand the same into frictional contact with said outer member by pressure produced on the lead in the lead-feeding stem tending to force the same back into the pencil, to hold said members against relatively longitudinal adjustment, and yielding means operative on the lead-feeding stem tending to cause the expanding member to expand said inner member or permit said expanding member to move under the contracting action of said inner member to release the same from the outer member.
- 35 9. A pencil including a casing comprising relatively longitudinally adjustable telescopically connected inner and outer members, a lead-feeding stem attached to the inner casing member for longitudinal adjustment therewith, co-operating ratchet-acting means on said members for causing a step by step movement to the lead-feeding member during relatively longitudinal adjustment of the casing members, and an expanding member on the lead-feeding stem arranged to be operated by pressure produced on the lead in the lead-feeding stem tending to force the same into the pencil to hold said ratchet-acting means inactive and prevent relative longitudinal adjustment of the casing members.
- 40 10. A pencil including a casing comprising relatively longitudinally adjustable telescopically connected inner and outer members, a lead-feeding stem attached to said inner member for longitudinal adjustment therewith, said outer member having a plurality of longitudinally spaced corrugations, a bead on said inner member adapted to enter said corrugations and ride thereover with a ratchet-like action during the relative longitudinal adjustment of the casing members, said inner member being free for contracting and expanding movements, an expanding member on said stem for expanding said inner member onto said outer member with the bead in one of the corrugations, and yielding means operative on said stem and under strain to cause the expanding member to expand said inner member onto said outer member or permit said expanding member to move under the contracting action of the inner casing to release the same from the outer casing.

In testimony whereof I affix my signature.

FRANK J. VIERLING.
